UNITED STATES PATENT OFFICE.

ADELBERT AMES, JR., OF TEWKSURY, MASSACHUSETTS.

PROJECTION APPARATUS.

1,216,910.

Specification of Letters Patent. Patented Feb. 20, 1917.

Application filed June 6, 1916. Serial No. 102,085.

To all whom it may concern:

Be it known that I, ADELBERT AMES, Jr., a citizen of the United States, and resident of Tewksbury, in the county of Middlesex and State of Massachusetts, have invented new and useful Improvements in Projection Apparatus, of which the following is a specification.

This invention relates to light projection apparatus designed to project a sharply defined, concentrated beam of light a considerable distance. More particularly the invention relates to a headlight for use on automobiles and the like adapted to illuminate the roadway far in advance of the vehicle without producing upward glare, that is, without projecting substantially any light above a horizontal plane passing through the region of the light source, and at the same time adapted to produce distributed illumination for relatively short and intermediate distances along the roadway.

In my prior application Serial No. 72,503, filed January 17, 1916, I have disclosed light projection apparatus having a reflector comprising two or more surfaces each having a contour generated by the partial revolution of a conic section. Suitable contours of this character comprise, for example, paraboloids and ellipsoids. Suitable arrangements of a plurality of such surfaces comprise, for example, a paraboloidal surface forming substantially the lower half of the reflector and an ellipsoidal surface forming substantially the upper half of the reflector, or a paraboloidal surface forming substantially each half of the reflector, the light source being in the region of the plane dividing the two surfaces.

When employing an ellipsoidal surface for the upper half of the reflector and a paraboloidal surface for the lower half thereof, for example, most of the upward glare may be eliminated by so arranging the two surfaces that one of the two foci of the ellipsoidal surface substantially coincides with the focus of the paraboloidal surface, with the other focus of the ellipsoidal surface lying in front of the common focus, and positioning the light source to the rear of the common focus. With this arrangement the light reflected from the paraboloidal surface may be projected in and below a horizontal direction while the light reflected from the ellipsoidal surface may be projected downwardly and in the general direction of the

second focus of the ellipsoid. Other arrangements of a plurality of surfaces of the general character described also may be employed with good results.

However, in nearly all cases where the axes of the reflector surfaces are positioned substantially horizontally to afford a concentrated beam of light which can be projected a considerable distance along the roadway, some light is projected in an upward direction. This I have found to be due to the fact that, inasmuch as all light sources have appreciable dimensions, parts of the light source are necessarily displaced relatively to the foci of the reflecting surfaces and relatively to the substantially horizontal plane containing the axis of one or both of the reflecting surfaces. The major portion of the glare due to this fact can be avoided by properly positioning the light source relatively to the foci of the reflecting surfaces. For example, when employing a paraboloidal surface for the lower half of the reflector and an ellipsoidal surface for the upper half thereof, with the rear focus of the ellipsoidal surface coincident with the focus of the paraboloidal surface, most of the upward glare can be avoided by positioning the light source behind the common foci. The remaining glare can be eliminated by shifting the light source upwardly as well as rearwardly, so that it lies behind and above the focus of the paraboloidal surface as hereinafter explained.

However, for some purposes it is desirable to keep the light source in the axis of the reflector, particularly in the case of a paraboloidal reflector as, for example, for the purpose of maintaining strong concentration of light in an axial direction.

The principal object of this invention is to eliminate upward glare in headlights of the class described under the above and similar circumstances, and at the same time to utilize all or substantially all of the reflecting surfaces to project a concentrated beam of light in substantially an axial direction, whereby a beam of light sharply defined by a horizontal plane passing through the region of the light source and having a high degree of concentration in an axial direction may be produced.

In the accompanying drawings which are largely diagrammatic,—

Figure 1 shows one embodiment of my invention, wherein a band of frosted glass is

employed on the horizontal, central portion of the glass cover;

Fig. 2 is a front view of the apparatus illustrated in Fig. 1;

5 Fig. 3 shows another embodiment of my invention in which a non-reflecting band is provided on the reflector surfaces adjacent a horizontal plane through the region of the light source;

10 Fig. 4 is another embodiment of the invention showing a prism positioned in front of the light source;

15 Fig. 5 is another embodiment of the invention showing the reflector surfaces modified in contour adjacent the said horizontal plane;

20 Fig. 6 is another embodiment of the invention showing the light source positioned above and behind the foci of the reflecting surfaces;

Fig. 7 is a longitudinal, vertical section through a headlight having an auxiliary source of light;

25 Fig. 8 is a front elevation of the apparatus shown in Fig. 7;

Fig. 9 is an embodiment of my invention in which the upper reflecting surface is extended below a horizontal plane passing through the light source;

30 Fig. 10 is a front view of Fig. 9;

Fig. 11 shows a further modification of this invention in which the lower reflecting surface is extended above the said horizontal plane; and

35 Fig. 12 is a front view of Fig. 11.

In the embodiments of the invention shown in Figs. 1 to 10 inclusive, the portion F of the reflector above the horizontal plane passing through the region of the light source comprises an ellipsoidal surface, while the portion F' of the reflector below the said horizontal plane comprises a paraboloidal surface. With one of the foci f of the ellipsoidal surface and the focus f' of the paraboloidal surface at the same point and with a point source of light positioned at this point, in this type of reflector, all the light reflected from the lower surface would be projected in an axial direction, and all the light reflected from the upper surface would pass through the second focus of the ellipsoidal surface and be distributed along the roadway in front of the headlight. However, owing to the fact that all light sources have appreciable dimensions, some of the parts of the source must of necessity be displaced relatively to the foci of the reflecting surfaces. The following brief outline will indicate the effect of the displacement of the light source in the various directions from the focus of a paraboloidal surface.

If a point source of light is displaced in a forward axial direction, in a paraboloidal reflector, the light issuing therefrom will be

reflected toward the axis, and with the reflecting surface below a horizontal plane containing the axis, as illustrated in the drawings, the light will be radiated in an upward direction. In Fig. 1, for example, 75 a ray of light 1 radiating from a point 2 axially displaced in front of the focus f' of the paraboloidal reflector F' and striking the reflector at 3, would be reflected in an upward direction as indicated. Any ray issuing from the focus will be reflected horizontally, as illustrated for example, by rays 4 and 5. A ray of light emanating from a point in the axis of the reflector behind the focus thereof will be reflected in a direction 80 diverging from the axis and therefore in a downward direction. In Fig. 1 for example, a ray 6 issuing from the rear point of the filament L and striking the reflector at point 8 will be reflected downwardly as indicated. A ray issuing in a plane containing the axis of the reflector from a point displaced from the axis will be reflected inwardly or outwardly, and therefore upwardly or downwardly with the reflecting 90 surface below the axis thereof, depending upon whether or not the path of the ray intersects the axis in front of the focus. Thus, the path of the ray 11 issuing in the plane of the paper from point 12 and striking the 95 reflector at 13 intersects the axis behind the focus and is reflected outwardly and downwardly.

In the preceding paragraph only rays in planes including the axis of the reflector 100 were considered, that is, only the effect of the paraboloidal curvature of the reflector was considered. A paraboloidal reflector may also be considered as being made up of a plurality of circular elements lying respectively, in planes perpendicular to the axis. Upward glare also results from axial displacement of points of the light source owing to this circular curvature.

Considering points of light 21, 22 and 23 110 in Fig. 12, for example, which are radially displaced from the focus f' in a plane perpendicular to the axis of the paraboloidal surface and containing the focus and the circular element 24, and considering only the 115 effect of the circular curvature of the surface upon the rays of light issuing from the said points, in the said plane, the angles which the incident rays make with the radii of the circular element will be equal, respectively, to the angles which the corresponding reflected rays make with the radii. Thus, the incident and reflected rays 25 make equal angles α with the radius 30. The same is true of rays 26, 27, 28 and 29, and, if affected 120 only by the circular curvature of the reflector these rays would be reflected as indicated by the dash lines 25 to 29.

However, due to the combined circular and parabolic curvature the rays 25 to 29 130

would be reflected forwardly from the reflector, out of the vertical plane containing the focus, the points 21 to 23, and the circular element 24 of the reflector, and the actual directions taken by these rays would be such that the projection of the rays upon the said vertical plane would be as indicated at 35, 36, 37, 38 and 39, respectively, as will be apparent from the following considerations.

A plane tangent to any point in the circular element 24 of the paraboloidal reflector would make an angle of 45° with a line drawn from the focus to the said point. In Fig. 11, for example, a plane represented by the dash line 19, tangent to the reflector at point 20, makes an angle of 45° with the line connecting the point 20 and the focus. A ray of light emanating from the focus and incident to the reflector at point 20 would be reflected in a horizontal direction and the projection of the reflected ray on a plane perpendicular to the axis of the reflector, as for example, the plane 25 of the paper in Fig. 12, would appear as a point. The same is obviously true of all rays issuing from the focus and incident to the reflector on the element 24. Now the result of moving the light source from the focus in the said vertical plane is to deflect the reflected ray in a direction having a component tangential to the element 24 and the amount of tangential deflection depends upon the normal distance from the focus to the path of the ray. Thus the dash lines 35 to 39 roughly indicate the relative tangential deflection of the respective rays 25 to 29 due to the displacement of the light source points 21 to 23. Each of these reflected rays may have a direction having a component tangential to the circular element.

It will be noted that all incident rays lying in lines crossing the vertical plane containing the axis above the axis, such as rays 25 and 26, are deflected downwardly and that all incident rays lying in lines crossing the said vertical plane below the axis, such as rays 27, 28 and 29, are deflected upwardly. And while I have only shown rays in the transverse plane through the focus of the reflector for the purpose of illustrating the effect of radial displacement of points of the light source, it will be apparent that 55 radial displacement will produce similar effects on rays emanating in planes behind and in front of the focus and also upon rays which emanate at angles to planes perpendicular to the axis.

60 Thus, due to circular curvature, displacement of points of the light source above the horizontal plane of the axis of the parabolic surface tends to cause downward deflection of the reflected rays, displacement of points 65 of the light source below the horizontal

plane tends to cause an upward deflection of the reflected rays, and lateral displacement tends to cause upward or downward deflection depending on whether the paths of the rays extend below or above the axis. And, 70 due to paraboloidal curvature, displacement of the light source to the rear of the focus tends to cause outward, and consequently downward deflection where the paraboloidal surface is below the axis thereof, while forward displacement of the source tends to cause inward and hence upward deflection.

At any point intermediate the axis and the plane through the focus perpendicular to the axis the effects of the circular and 80 paraboloidal curvatures act either cumulatively or differentially depending upon the direction of the point from the focus and depending upon the direction of radiation of the particular ray.

Considering four zones produced by a horizontal plane containing the axis and a vertical plane through the focus perpendicular to the axis, it can be said, in general, that rays emanating from points in the rear, 90 upper zone will be reflected downwardly and horizontally inasmuch as rearward displacement tends to produce downward deflection due to the parabolic curvature, and upward displacement tends to produce 95 downward deflection due principally to the circular curvature. Hence, in the embodiments of my invention illustrated in Figs. 6 and 7, where the light source is positioned in the said rear, upper zone, no upward 100 glare would result. The source may, if desired, be so placed in any or all of the other embodiments. As above stated, however, it is at times desirable to keep the light source in the axis of the paraboloidal reflecting surface and in Figs. 1 to 5 and Figs. 9 and 10, I have shown the light source in the axis to the rear of the focus.

The ordinary commercial light source employed in headlights comprises either a V-shaped filament substantially as illustrated in the drawings or a helical filament. Thus parts of the filament necessarily will be displaced relatively to the axis. With the filament placed behind the focus of the paraboloidal reflector, as shown for example in Fig. 1, all rays radiating rearwardly and striking the reflector at a point below point 10 will be projected in or below a horizontal direction owing to the fact that all such 115 rays appear to come from points behind the focus. However, rays striking the reflector above point 10 are projected, slightly above the horizontal direction as illustrated by rays 1 and 4, for the reasons above set 120 forth. Some means, therefore, is required to prevent upward glare due to the rays incident to the paraboloidal surface in the rear of the light source.

Upward glare is not caused solely by that 130

region of the reflector in the rear of the light source, but also is caused to some extent by the side portions of the reflector adjacent the horizontal plane through the light source. This source of glare is due principally to vertical displacement of points of the light source relative to the aforesaid horizontal plane and to the circular curvature of the reflector as will now appear.

Referring again to Fig. 12, which illustrates the effect of the circular curvature of the reflector, it will be noted that the upward (or downward) tendency of the horizontal components of the reflected rays increases from a minimum below the axis to a maximum at points adjacent the horizontal plane containing the axis of the reflector. Thus, due to vertical displacement of points relative to the plane, upward glare is most likely to result from portions of the reflector adjacent the said horizontal plane.

Furthermore, the tendency to deflect the rays downwardly due to the parabolic curvature produced by shifting the light source rearwardly, is a minimum in the case of rays radiated approximately horizontally and striking the reflector adjacent the said horizontal plane, for the effect on all rays of shifting the light source rearwardly of the focus is to increase the divergence of the rays from the axis; and the downward component due to this increased divergence is a maximum below the axis and a minimum adjacent the horizontal plane through the axis.

Thus, while tendency toward glare from the major portion of the lower reflector can be readily counteracted by shifting the light source rearwardly of the focus, it is necessary to provide special means to prevent upward glare from the portions of the reflector adjacent the aforesaid horizontal plane in order to obtain a concentrated beam of light which can be projected a considerable distance without producing upward glare.

Some upward glare is also caused by the rays which emanate from points of the light source below the axis and which strike the upper half of the reflector F adjacent the horizontal plane, as shown in Fig. 4 by ray 16 issuing from point 17 and striking the reflector F at 18. This is ordinarily true whether the upper surface be paraboloidal, ellipsoidal or of other contour formed by the revolution of a conic section. However, when employing an ellipsoidal surface for the upper half of the reflector, as shown in Figs. 1 to 10, the tendency to reflect the rays upwardly is limited to the portion of the ellipsoidal surface in immediate proximity to the horizontal plane containing the axis for the reasons above mentioned in connection with the portion of the lower reflecting

surface adjacent the said horizontal plane, and for the further reason that an ellipsoidal surface positioned with both foci substantially in the said horizontal plane tends to project the rays reflected therefrom in a downward direction. By my invention the upward glare due to the aforesaid causes may be avoided by employing any one of a number of specific means.

In the embodiment of my invention shown in Figs. 1 and 2, the transparent cover G of the reflector is rendered translucent by means of a band of frosted glass FG across the horizontal central portion thereof. By this means all the rays which strike the two halves of the reflector adjacent the horizontal plane containing the axes of the two surfaces and which would otherwise be reflected in a direction slightly above the horizontal, will be diffused by means of the band of frosted glass, and thus be rendered unobjectionable.

In Fig. 3 the portions of the ellipsoidal reflector F and the paraboloidal reflector F' adjacent the horizontal plane containing the axes of these reflectors is rendered non-reflecting by suitable means, as for example, by means of a band of black paint NF. Thus the rays incident to these portions of the reflecting surfaces which would otherwise be reflected upwardly are absorbed by the non-reflecting surface.

In Fig. 4 a prism P horizontally disposed across the central portion of the reflector serves to deflect downwardly the rays which are incident to the reflecting surfaces adjacent the horizontal plane and which are reflected in a direction slightly above the horizontal. The prism is shown as being formed as an integral part of the glass cover G, but it may be constructed and supported in any desired manner.

In the specific embodiment of my invention shown in Fig. 5, the curvature of each of the two halves of the reflector is modified adjacent the horizontal plane in such a manner as to project the rays which emanate approximately horizontally from points of the light source displaced below the horizontal plane in or below a horizontal direction. This result can be accomplished by making a narrow portion M of the ellipsoidal surface adjacent the said horizontal plane tangent to the remaining ellipsoidal portion. The paraboloidal half of the reflector may be modified adjacent the horizontal plane by curving the surface inwardly, as at M'. A suitable contour for the upper margin of the paraboloidal half of the reflector will be produced by giving the margin a curvature toric in character, having a radius r , and a locus of centers on a line parallel to the paraboloid in a plane parallel to the horizontal axial plane and at distance $o-o$ therefrom.

Two or more of the specific means for accomplishing the objects of my invention may be employed in a single projector. In Fig. 6, for example, I have shown the reflectors modified in curvature adjacent the horizontal plane as in Fig. 5, a prism P as in Fig. 4, and the light source L positioned above and behind the common focus f' of the two reflecting surfaces. However, it is to be understood that either one of the three expedients herein illustrated would suffice if properly and accurately applied.

In Figs. 7 and 8 I have shown the upper ellipsoidal surface F reduced in size to such an extent that the central element thereof forms a smooth curve with the central element of the paraboloidal surface F'. With this construction, the rear casing C of the projector may be made of parabolic contour throughout with the ellipsoidal reflector contained wholly within the casing. Furthermore, an auxiliary source of light AS may be placed in the upper central portion of the projector for use where only a signal light is desired. The front portion of the projector surrounding the auxiliary source of light may be inclosed by suitable means C'.

In this embodiment of my invention the focus f' of the paraboloidal surface is positioned above and in front of the focus f of the ellipsoidal surface F, and the light source L is positioned between the two foci. This arrangement avoids upward glare for the following reasons: With relation to the paraboloidal surface, upward glare is avoided owing to the fact that the light source is positioned to the rear of the focus f' and owing to the fact that the source is positioned above the horizontal plane dividing the two reflecting surfaces. With relation to the ellipsoidal surface, upward glare is avoided owing to the fact that all rays incident thereto emanate from points in front of the first focus f and therefore cross the horizontal plane behind the second focus of the ellipsoidal surface. Ordinarily, the second focus of the ellipsoidal surface would be positioned in the same horizontal plane with that of the first focus f , but in order to project the diverging beams of light formed by the ellipsoidal surface farther up the roadway, the second focus may be positioned above the horizontal plane.

I have illustrated diagrammatically another embodiment of my invention in Figs. 9 and 10, wherein the ellipsoidal reflector F is reduced in size as in Figs. 7 and 8, and extended below the horizontal plane passing through the region of the light source within the ellipsoidal reflecting surface. The lower portion 42 of the upper half of the reflector is made tangential to the remaining ellipsoidal portion beginning a short distance above the horizontal plane, as in Figs. 5 and 6. In this arrangement the rays which emanate

from the portions of the light source below the horizontal plane containing the common focus and which would otherwise be reflected in an upward direction from the portions of the reflecting surface adjacent to said horizontal plane will be deflected downwardly by the extended portion of the ellipsoidal surface.

Figs. 11 and 12 illustrate still another species of my invention, in which the lower half of the reflector is extended above the horizontal plane through the region of the light source within the upper half of the reflector, and the upper portion 44 of the lower half is modified as in Figs. 5 and 6 to prevent upward glare due to rays emanating substantially horizontally from points of the light source displaced below the horizontal plane containing the axes of the two reflecting surfaces. Owing to the fact that the lower surface is extended above the horizontal plane, the portion of the upper reflecting surface adjacent the said plane is shielded from the light source and need not be modified in curvature as in Figs. 5 and 6. In this species of my invention I have shown both the lower reflector F' and the upper reflector F'' as of paraboloidal contour.

In each of the modifications of my invention, the means provided on either side of the horizontal plane through the light source should in practice be extended for a somewhat greater distance on either side of the said plane than is theoretically necessary in order to provide a safety factor to take care of such variable factors as differences in sizes of commercial light sources and imperfections and inaccuracies in the shape and relative positions of the various parts of the projector.

Furthermore, I have found that upward glare results from portions of the reflector farther removed from the horizontal plane through the light source in the region behind the light source than in the other regions adjacent the said horizontal plane, namely, the side regions of the reflector. For this reason I preferably provide, for the region behind the light source, glare preventing means of additional width. For example, in Fig. 1 a circle of frosted glass FG', having a greater diameter than the width of the band of frosted glass FG, is provided at the center of the glass cover; and in Fig. 3 semi-circles of non-reflecting surface NF', having greater diameters than the width of the two non-reflecting bands NF, is provided back of the light source. In Figs. 9 and 10, the skirt 42 extending below the horizontal plane of the light source has a lip 43 at the central portion of its lower edge; and, in Figs. 11 and 12, the extension 44 has a lip at 45 at the central portion of its upper edge.

However, instead of providing wider glare preventing means at the central portion of

the headlight than at the sides the means may have the larger dimension throughout the entire width of the reflector. For example, in Figs. 4 and 6 the glass prisms P have vertical dimensions equal to the diameter of the circle of frosted glass FG' in Fig. 2; and, in Figs. 5 and 6 the modified curvatures of the reflectors adjacent the horizontal plane through the light source have substantially the same width throughout as the vertical dimension of the non-reflecting surfaces NF behind the light source in Fig. 3.

While I have described a single reflecting surface above and below the horizontal plane respectively, it is to be understood that each of these surfaces may be made in the form of a compound surface comprising a plurality of segments each having a different degree of curvature, as disclosed for example in my prior application Serial No. 72,503, filed January 17, 1916, in the event that light distribution other than that obtainable by means of single curvatures is desired.

Another feature of my apparatus comprises a cover for the projector arranged to prevent upward glare due to light being reflected from the rear face of the glass front cover to the projector and thence upwardly. Owing to the fact that the percentage of light reflected backwardly from the headlight cover increases with increase of the angle of incidence from about 5% at normal incidence to almost 100% at grazing incidence, an appreciable amount of light would be reflected from the portions of the cover adjacent the periphery thereof when employing an ordinary flat glass cover. In my improved apparatus designed to project a beam of light sharply defined at one side, this reflected light is decidedly objectionable. In Fig. 4 I have illustrated this effect by a ray 50 reflected from the flat glass cover at 51 to the reflector F' at point 52 and thence projected upwardly. I overcome this difficulty by providing a front cover so shaped and positioned relative to the light source and to the paraboloidal reflector that either no substantial amount of light will be reflected from the said glass cover or, if a substantial amount is reflected, it will not strike the reflector at such an angle as to be projected upwardly. In Fig. 5, for example, I have shown one form of cover for accomplishing the desired result comprising a glass cover G' having a cylindrical portion 53 extending rearwardly therefrom. Thus the flat portion of the cover is positioned farther forward so that the light is incident thereto at more nearly normal incidence, resulting in less light being reflected therefrom. Furthermore, most of the light which is reflected will not strike the projector but will pass through the cylindrical

portion 53 of the cover as shown in Fig. 5, by ray 54 incident to the glass cover at 55. While I have only shown a special cover in Fig. 5, it is to be understood that it may, and preferably should, be used with each form of non-glare headlight.

In this particular type of reflector it is also essential to have the light source substantially at or in front of the center of the glass bulb inclosing it, inasmuch as some light is reflected inwardly from the glass bulb which otherwise will strike the reflecting surfaces at such angles as to be projected upwardly. For example, with the light source displaced behind the center of the bulb the reflected light will focus at a point displaced in front of the center of the bulb a distance equal to the rearward displacement of the light source. The light thus reflected and focused radiates from the focus point to the reflectors as from a light source positioned at this point. And, due to the forward displacement of the point, upward glare results owing to the effect of forward displacement above described.

It is to be understood that the words horizontal, vertical, upward, downward, etc., are used throughout the specification and claims merely for convenience in referring to relative locations and directions, and that my invention is not limited to headlights employed solely in the position herein described. On the contrary, the invention is applicable wherever it is desired to project a beam of light sharply defined on at least one side. I contemplate, for example, applying my invention to search-lights employed to illuminate buildings and the like.

I claim:

1. Light projection apparatus comprising a reflector, and a light source having at least two substantial dimensions, the reflector being shaped and positioned with relation to the light source to reflect in and below a horizontal direction a concentrated beam of light sharply defined on its upper side and to project substantially no light upwardly.

2. Light projection apparatus comprising a reflector adapted to reflect in and below a horizontal direction, a concentrated beam of light sharply defined on its upper side, and a light source having a portion vertically displaced with relation to a horizontal plane through the focus of the reflector and positioned with relation to the focus so that substantially no light is reflected upwardly.

3. Light projection apparatus comprising a reflector adapted to project a concentrated beam of light in and below a horizontal direction, a light source having a substantial vertical dimension and positioned with relation to the focus of the reflector so as to reflect in and below a horizontal direction substantially all rays of light radiating relatively obliquely to a horizontal plane pass-

ing through the light source, and means adjacent said horizontal plane for preventing substantially all rays of light radiating either parallel with or relatively acutely to said horizontal plane from being reflected upwardly, whereby a concentrated beam of light may be projected substantially horizontally without producing upward glare.

4. Light projection apparatus comprising a reflector having substantially a contour formed by the revolution of a conic section, a light source positioned with relation to the focus of the reflector so as to reflect in and below a horizontal direction substantially all rays of light radiating from the source other than those rays radiating approximately horizontally, and means adjacent a horizontal plane passing through the light source for preventing substantially all rays radiating approximately horizontally from being reflected upwardly, whereby a concentrated beam of light may be projected substantially horizontally without reflecting substantially any light upwardly.

5. Light projection apparatus comprising a reflector having substantially a contour formed by the revolution of a conic section and arranged to reflect a concentrated beam of light in and below a horizontal direction, a light source positioned with relation to the focus of the reflector so as to reflect substantially no light upwardly except in the region of a horizontal plane through the light source, and means adjacent said horizontal plane for preventing substantially all light radiating in horizontal and nearly horizontal directions from being reflected upwardly, whereby a concentrated beam of light may be projected substantially horizontally without reflecting substantially any light upwardly.

6. Light projection apparatus comprising a light source having an appreciable vertical dimension, a reflector having a portion above and a portion below a horizontal plane through the light source, one portion of the reflector being shaped and positioned with relation to the light source to project a concentrated beam horizontally, and the other portion being shaped and positioned with relation to the light source to project a divergent beam downwardly, and means adjacent said horizontal plane for preventing from being reflected upwardly substantially all rays radiating approximately horizontally from the light source, whereby a beam of light may be projected to distant, near and intermediate portions of a roadway without producing upward glare.

7. Light projection apparatus comprising a light source, a paraboloidal reflector positioned below the light source in such manner as to project a concentrated beam of light horizontally, a reflector having substantially a contour formed by the revolution of a

conic section positioned above the light source in such manner as to project a divergent beam of light downwardly, the light source being displaced rearwardly and vertically with relation to the focus of the paraboloidal reflector, and means adjacent a horizontal plane through the light source for preventing from being reflected upwardly substantially all rays radiating approximately horizontally from the vertically displaced portions of the light source, whereby a beam of light may be projected to distant, near and intermediate portions of a roadway without producing upward glare.

8. Light projection apparatus comprising a light source, a paraboloidal reflector positioned at least in part on one side of a horizontal plane through the light source so as horizontally to project a concentrated beam of light a considerable distance along a roadway, a concave reflector positioned at least in part on the other side of said plane so as downwardly to project a divergent beam of light to near and intermediate portions of the roadway, the light source being positioned at the focus of the paraboloidal reflector but having portions axially and vertically displaced with relation to the focus, and means adjacent a horizontal plane through the light source operative only upon light radiating approximately horizontally from the source for preventing such light from being reflected upwardly.

9. Light projection apparatus comprising a reflector having a substantially paraboloidal portion, and a light source positioned with relation to the focus of the reflector so as to reflect in and below a horizontal direction substantially all rays of light incident to the said paraboloidal portion, the curvature of the reflector being modified adjacent a horizontal plane through the light source in such manner that substantially all rays radiating approximately horizontally from the light source are prevented from being reflected upwardly, whereby a concentrated beam of light may be projected substantially horizontally without reflecting substantially any light upwardly.

10. Light projection apparatus comprising a reflector the major portion of which has substantially a contour formed by the revolution of one or more conic sections, and a light source positioned with relation to the focus or foci of the reflector so that substantially all rays of light striking the said portion of the reflector are reflected in and below a horizontal direction, the light source having portions radially displaced from the axis of the reflector, and the reflector having, adjacent a horizontal plane through the light source, a portion modified in such manner that light radiating from the said displaced portions of the light source approximately parallel with said plane are not

reflected upwardly, whereby a concentrated beam of light may be projected substantially horizontally without reflecting substantially any light upwardly.

- 5 11. Light projection apparatus comprising a reflector adapted to reflect, in and below a horizontal direction, a concentrated beam of light, a light source having a portion vertically displaced with relation to a 10 horizontal plane through the focus of the reflector and positioned with relation to the focus so that substantially no light is reflected upwardly, and a transparent container for the light source, the light source 15 being positioned at or in front of the center of the container to prevent light being reflected from the interior surface thereof to the reflector in such manner as to be reflected upwardly.
- 20 12. Light projection apparatus comprising a reflector adapted to reflect in and below a horizontal direction, a concentrated beam of light sharply defined on its upper side, a light source having a portion vertically displaced with relation to a horizontal 25 plane through the focus of the reflector and positioned with relation to the focus so that substantially no light is reflected upwardly, and a transparent front cover for the reflector shaped and positioned to prevent substantially any light being reflected therefrom to the reflector in such manner as to be projected upwardly.

- 30 13. Light projection apparatus comprising a light source, and a reflecting surface positioned substantially wholly below a horizontal plane passing through its focus, the reflecting surface being shaped and positioned to project a concentrated beam of 35 light horizontally, the light source being positioned immediately behind the focus and immediately above the axis so that substantially no light is projected upwardly.

- 40 14. Light projection apparatus comprising a light source, and a reflecting surface positioned substantially wholly on one side of a horizontal plane passing through its focus and adapted to project a concentrated beam of light horizontally, the light source 45 being placed in juxtaposition to the focus of the reflecting surface but lying substantially entirely on one side of the focus along the axis and lying substantially wholly above said plane so that substantially 50 no light is projected upwardly.

- 55 15. Light projection apparatus comprising a light source, and a reflector shaped and positioned to project a concentrated beam of light horizontally, the light source 60 being positioned, with respect to the focus of the reflector, rearwardly and upwardly and in such manner that the concentrated beam of light is sharply defined on its upper side.

65 16. Light projection apparatus comprising a reflector, and a light source having portions radially displaced from the axis of the reflector, the reflector being so shaped and the light source being so positioned with respect to the focus or foci of the reflector 70 as to prevent light radiating from the source being reflected upwardly due either to the transverse or to the longitudinal curvature of the reflector and as to project in and below a horizontal direction a concentrated 75 beam of light sharply defined on its upper side.

17. Light projection apparatus comprising a light source, a reflector having a reflecting surface above and a reflecting surface 80 below a horizontal plane through the light source and arranged to project light from both surfaces, the light source having a substantial dimension along the axis of the reflector, and the reflector being constructed 85 and positioned with relation to the light source horizontally to reflect a concentrated beam of light sharply defined on its upper side and downwardly to reflect a divergent beam of light, whereby distant, near and 90 intermediate portions of the roadway may be adequately illuminated.

18. Light projection apparatus comprising a reflector adapted to reflect, in and below a horizontal direction, a concentrated beam of light sharply defined on its upper side, and a light source having a portion vertically displaced with relation to a horizontal plane through the focus of the reflector and positioned with relation to the 100 focus so that substantially no light is reflected upwardly, the reflector having a surface of substantial extent both above and below said horizontal plane for projecting said beam of light. 105

19. Projection apparatus comprising a reflector and a light source, the reflector being so constructed and the light source being so positioned with respect to the focus or foci of the reflector as to project a concentrated beam of light substantially horizontally, the light source having portions radially displaced from the axis or axes of the reflector, and means for preventing light radiating from the displaced portions of 110 the source from being reflected upwardly due to the transverse curvature of the reflector. 115

20. Light projection apparatus comprising means for projecting in and below a horizontal direction, a concentrated beam of light sharply defined on its upper side, said means including a reflector and a light source so positioned with respect to the focus or foci of the reflector that substantially no light is projected upwardly, and a transparent front cover for the reflector arranged to prevent substantially any light 120 125

from being reflected therefrom to the reflector in such manner as to be projected upwardly.

21. Light projection apparatus comprising means for projecting, in and below a horizontal direction, a concentrated beam of light sharply defined on its upper side, said means including a reflector and a light source so positioned with respect to the 10 focus or foci of the reflector that substantially no light is projected upwardly, and a transparent container for the light source, the container being so shaped and positioned with respect to the source that substantially 15 no light is reflected from the interior surface of the container to the reflector in such manner as to be projected above the sharply defined upper side of said concentrated beam of light.

22. Light projection apparatus for projecting, in and below a horizontal direction, a concentrated beam of light, comprising a reflector, a light source so positioned with respect to the focus or foci of the reflector 25 that substantially no light radiating relatively obliquely to a horizontal plane through the light source is projected upwardly, means adjacent said horizontal plane for preventing from being reflected upwardly substantially all rays of light radiating either parallel with or relatively acutely to said horizontal plane, and a transparent container for the light source so shaped and positioned with respect to the 30 source that substantially no light is reflected from the interior surface thereof to the reflector in such manner as to be projected upwardly.

23. Light projection apparatus for projecting a concentrated beam of light substantially horizontally comprising a substantially hemi-paraboloidal reflector positioned below a horizontal plane containing its axis, a light source positioned rearwardly 45 of the focus of the reflector in such manner that light is projected to distant, near and intermediate portions of a roadway without producing upward glare, and a transparent container for the light source positioned with respect to the light source in 50 such manner that substantially no light is reflected from the interior of the container to the reflector in such manner as to be projected upwardly.

24. Light projection apparatus comprising a light source, a reflector having a portion above and a portion below a horizontal plane through the light source, one portion of the reflector being shaped and positioned 60 with relation to the light source to project a concentrated beam of light horizontally, and the other portion being shaped and positioned with relation to the light source to project a divergent beam downwardly,

the foci of the two respective portions of 65 the reflector being axially displaced with respect to each other, and the light source being positioned between parallel transverse planes through the respective foci.

25. Light projection apparatus comprising 70 a concave reflector and a light source, the reflector being so shaped and the light source being so positioned on one side of a transverse plane through the focus of the reflector as to project a concentrated beam 75 of light along and below a horizontal plane through said focus without producing upward glare, and a transparent container for the light source, the container being so shaped and the light source being so positioned within the container as to prevent the light reflected from the inner surface of the container from being reflected to the reflector in such manner as to cross said horizontal plane on the side of said transverse 80 plane opposite to the light source.

26. Light projection apparatus comprising a concave reflector and a light source, the reflector being so shaped and the light source being so positioned on one side of 90 a transverse plane through the focus of the reflector as horizontally to project a concentrated beam of light without producing upward glare, and a transparent container for the light source, the container being so shaped and the light source being so positioned within the container as to prevent the light reflected from the surface of the container from focusing at a region other than on the same side of said plane as the 95 light source and farther from the focus than the light source.

27. Light projection apparatus comprising a substantially hemi-paraboloidal reflecting surface positioned below a horizontal 105 plane containing its axis, a light source so positioned behind a transverse plane through the focus of the reflecting surface as horizontally to project a concentrated beam of light without producing upward 110 glare, and a transparent container for the light source, the container being so shaped and the light source being so positioned within the container as to cause the light reflected from the surface of the container 115 to cross said horizontal plane rearwardly of the focus.

28. Light projection apparatus comprising a concave reflector and a light source arranged to project a beam of light horizontally, and a transparent container for the light source, the container being so shaped and positioned with respect to the light source and the reflector being so arranged with respect to the container that 120 substantially no light is reflected from the surface of the container to the reflector so as to be projected upwardly.

29. Light projection apparatus comprising a concave reflecting surface disposed at least in part on one side of a horizontal plane containing its axis, a light source disposed on one side of a transverse plane through the focus of the reflecting surface, and a transparent container for the light source, the container being so shaped and

positioned that substantially no light is reflected from its surface so as to cross said horizontal plane on the side of said transverse plane opposite to the light source. 10

Signed by me at Boston, Massachusetts, this 23rd day of May, 1916.

ADELBERT AMES, Jr.
